Primary Examiner — Alison M Ofstun*Assistant Examiner* — Evin F Ershock(74) *Attorney, Agent, or Firm* — The Law Office of Patrick F. O'Reilly III, LLC(57) **CLAIM**

The ornamental design for a finger toothbrush for a baby, as shown and described.

DESCRIPTION

FIG. 1 is a front perspective view of a finger toothbrush for a baby, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the figures show portions of the finger toothbrush that form no part of the claimed design.

1 Claim, 7 Drawing Sheets(56)
